UNITED STATES PATENT OFFICE.

ALFRED J. MACY, OF CHICAGO, ILLINOIS, ASSIGNOR TO MACY ENGINEERING COMPANY, OF FRANKLIN, PENNSYLVANIA, A CORPORATION OF MAINE.

STABILIZER.

1,327,055.

Specification of Letters Patent.

Patented Jan. 6, 1920.

Application filed March 25, 1916. Serial No. 86,610.

To all whom it may concern:

Be it known that I, ALFRED J. MACY, a citizen of the United States, and a resident of the city of Chicago, in the county of Cook and State of Illinois, have invented certain new and useful Improvements in Stabilizers; and I do hereby declare that the following is a full, clear, and exact description of the same, reference being had to the accompanying drawings, and to the numerals of reference marked thereon, which form a part of this specification.

This invention relates to an automatically acting mechanism for controlling or operating the controlling means for an airship in flight. Many different types of balancing or stabilizing devices have been designed heretofore with the end in view of automatically setting mechanisms in operation to actuate the controlling means for air vehicles and for adjustment of the guiding or balancing means. No attempt, however, has been made to provide a device designed to act differently according to the intensity or degree of deviation of the vehicle from a predetermined course or attitude of movement, nor to take into account the effect of upwardly or downwardly moving currents of air which, although they may not change the angular position of the machine relative to the earth, still do effect a change in the angle of incidence of flight of the machine, which may prove very dangerous.

It is an object therefore of this invention to construct a balancing or stabilizing device adapted to correct deviations in flight, for example of an aeroplane from its proper attitude by successive actuation of the controlling devices to secure increasing increments of adjustment thereof.

It is also an object of this invention to construct a balancing or stabilizing device for aeroplanes embracing a plurality of gravity acting means for the different controlling surfaces of the aeroplane acting independently to operate the same to maintain the aeroplane in a proper attitude in flight.

It is also an object of this invention to construct an automatically operating mechanism for adjusting the controlling means of a vehicle to maintain the same in a proper operative attitude with respect to the earth, said mechanisms adapted to operate differently for different degrees of deviation or

deflection of the vehicle from its proper attitude, so that the restoring effect bears a direct relation to the amount and abruptness of deviation of the vehicle, and furthermore said mechanism acting to correct the angle of flight of the machine when affected by cross currents which do not change the relative angle of the machine with respect to the earth, but may cause a dangerous angle of incidence to be set up.

It is also an important object of this invention to construct a stabilizing or balancing mechanism for aircraft embodying tiltably mounted instrument boards or tables, one for longitudinal and one for lateral controls, carrying circuit operating means thereon which, through interaction with gravity acting means mounted on said boards, act to operate controlling devices for the guiding and balancing means of the aeroplane, whereby a greater or increasing restoring effect is obtained to overcome increasing or abnormal deviations in flight of the aeroplane from its proper flying attitude.

It is furthermore an object of this invention to construct a balancing or controlling mechanism for a vehicle sensible to small deviations in movement thereof from a proper attitude and capable of operation with an increasing restoring effect for sudden and abrupt deviations of the vehicle from proper attitude.

The invention (in a preferred form) is illustrated in the drawings and hereinafter more fully described.

In the drawings:

Fig. 26 is a similar view of the spring for the other of said levers.

As shown in the drawings:

As shown in Figs. 1 and 2, the aeroplane consists of upper and lower surfaces 1 and 2, respectively, with a body 3, shown fragmentarily, mounted therebetween and with- 50 in which the power plant and operating mechanisms for the controls of the aeroplane are situated. The lateral controls or aile- 55 rons (not shown) are interconnected and operated by cables, that for the right wing of the aeroplane denoted by the reference numeral 4, and that for the left wing by the reference numeral 5. These cables lead into the operating compartment in the body 3, and are attached at their ends to the same up- 60 right shoulder piece 6, which is secured upon a shaft 7, journaled longitudinally in the body 3, permitting said shoulder piece to be oscillated by the shoulders of an operator seated within the body to thereby operate 65 the controlling cables 4 and 5. The oscil-

latory movement of the member 6, from nor- mal or central position is resisted by springs 6^a, connected on the framework of the body

3. At the forward end of said shaft 7, a U-shaped bracket or yoke 8, is secured there- 70 on, adapted to oscillate with said shaft 7,

due to the movement of said shoulder piece 6, or conversely to impart a movement through said shaft 7, to said shoulder piece 6, when operated. The means for operating 75

said yoke or bracket 8, constitutes the stab- 80 ilizing means of the aeroplane, and cables 9 and 10, respectively, are connected to said yoke 8, and lead through a partition 11, and over idler sheaves mounted on the rear sur- face thereof, and are there wound about drums hereinafter described, for actuating the same.

The cables for longitudinal control are denoted by the reference numerals 12 and 85

13, respectively, and are each connected to a pivoted lever 14, movement of which from normal or central position is resisted by

springs 14^a. Also connected to said lever 90

14, are cables 15 and 16, respectively, which lead through the partition 11, and are there trained about idler sheaves leading to the automatically controlled drums hereinafter described. A spring 17, is connected in the cable 16, to hold the same tensioned and 95

take up any slack in the other of the cables connected to said lever 14.

As clearly shown in Fig. 2, pivotally mounted at one side of the compartment in the body 3, is a vertical longitudinally dis- 100

posed longitudinal control instrument board 18, and adjacent thereto and rigidly mount- 105

ed is lateral control instrument board 19, extending transversely of the aeroplane. The instrument boards are exactly similar. 110

In construction and an enlarged detail view of the one for lateral control is shown in Figs. 3, 4, and 5. Pivotally mounted on the front surface of said lateral control board 19, which is preferably constructed 115

of any insulating material, such as wood, composition, fiber, or the like, is a small centrally disposed gravity acting main lateral plumb lever 21. Said main lateral lever 21, is provided on each edge thereof, as 120

shown in detail in Figs. 13 and 14, with springs 22^a and 22^b, respectively, affording contact points for terminal posts 23^a and 125

23^b, respectively. The lateral control board 19, is provided with two similar gravity 130

acting or plumb contact levers for the lateral controls of the aeroplane, and the contacts, circuits and controlling mechanisms operated thereby are exactly similar and identical in every respect, those mechanisms forming the part of the controlling means 135

for the control of the right wing having the sub-letter "a" appended to each of the reference numerals thereof, and the mechanisms for operating the left wing having 140

the sub-letter "b" appended to the reference numerals thereof.

Secured on said lateral control board 19, and insulated therefrom, are pintle bolts 24^a and 24^b, respectively, and surrounding each thereof, as shown in detail in Fig. 6, are insulating sleeves 25^a and 25^b, respectively. Hung pivotally on the outer end of each of the bolts 24^a and 24^b, respectively, are secondary gravity acting right and left lateral control plumb levers 26^a and 26^b. Secured on the inner edge of each of said secondary right and left lateral control plumb levers 26^a and 26^b, respectively, are resilient contact members 27^a and 27^b and secured upon the board 19, are adjustable terminal posts 28^a and 28^b, respectively, normally contacted by said plumb lever contact members. Also secured upon said lateral control board 19, on the outer side of each of said right and left lateral control plumb levers, are adjustable terminals 29^a and 29^b, respectively, each adapted to be contacted by the end of one of the contact springs 30^a and 30^b, respectively, also mounted on the board, but normally retained from contact with said terminals 29^a and 29^b, by L-shaped extensions 31^a and 31^b, respectively, on said plumb levers.

Journaled on each of the insulating sleeves 25^a and 25^b, respectively, are contact levers 32^a and 32^b, respectively, which project downwardly substantially parallel and at one side of the right and left lateral control plumb levers 26^a and 26^b, and at their lower ends are each provided with a contact point adapted to close against contact points provided on the respective plumb levers, and an L-shaped extension 33^a and 33^b, is provided respectively on said plumb levers to engage around said depending levers 32^a and 32^b, to limit movement thereof away from the plumb levers. Each of said contact levers 32^a and 32^b, respectively, is provided with a friction shoe denoted respectively by the reference characters 34^a and 34^b, shown in detail in Fig. 7, adapted to bear upon the insulating sleeves, and each adjustable by means of a threaded bolt and nut to increase or decrease the friction, so that there is a tendency for said contact levers to move as a stationary element with said lateral control board 19. Surrounding the hub extensions of each of said contact levers 32^a and 32^b, respectively, are insulating sleeves 35^a and 35^b, respectively, extending through said lateral control board 19, and journaled thereon are contact levers 36^a and 36^b, respectively, which also tend to move with said board, due to the frictional pivotal insulating support therefor. Formed on each of the plumb levers are long extensions 37^a and 37^b, respectively, adapted to engage over the end of the contact levers 36^a and 36^b, respectively, to limit the separation thereof from said right and left lateral control plumb levers. As clearly shown in detail in Fig. 6, metallic conductor sleeves or collars are provided for the respective levers 32^a and 36^a, and 32^b and 36^b, respectively, and connected to said metallic conductor sleeves are wires 38^a, 38^b, 39^a, and 39^b, respectively, and to the pivot bolts 24^a and 24^b, are connected the respective wires 40^a and 40^b.

Referring next to the magnetic clutches and drums actuatable thereby for the respective cables 9, 10, 15, and 16, mounted upon said partition 11, is a box or casing 41, having journaled horizontally therein an upper shaft 42, and a lower shaft 43. Secured centrally on each of said shafts are worm wheels 44 and 45, respectively, and projecting into the casing and journaled at its end therein, is a shaft 46, with a worm 47, secured thereon, meshing with said respective worm wheels, said shaft 46, connected in any suitable manner to be driven by the power plant or engine of the aeroplane, which may be denoted by the reference numeral 48, as shown in Fig. 17.

Rigidly associated with the worm wheel 44, is a pair of magnetic clutch elements 49^a and 50^c, respectively, and similarly associated with the worm wheel 45, to rotate therewith, are magnetic clutch elements 49^b and 50^d, respectively. Connected to co-act with said magnetic clutch elements are pinions 51^a, 51^b, 52^c, and 52^d, respectively, which are journaled to freely rotate on the respective shafts 42 and 43, and each is provided with a magnetic plate rigidly secured thereto adapted to be attracted by one of said magnetic clutch elements when the coils thereof are energized, so that the respective pinion is caused to rotate therewith.

Journaled in bearings provided for the purpose, is a shaft 53, parallel to said respective shafts 42 and 43, and journaled thereon are drums 54 and 55, each of which has rigidly connected thereto a relatively large gear 57 and 58, respectively, one for each of said drums, with the gear 57 meshing with the pinions 51^a and 51^b, and the gear 58 meshing with the pinions 52^c and 52^d, respectively. The construction of the magnetic clutches is well known, but a detail, however, is shown in Fig. 12, and as shown said magnetic clutch consists of a plurality of magnetic coils 59, connected to one another with one terminal grounded and the other leading to a contact ring 60, on the exterior of the insulating casing in which said coils are mounted, and a spring impelled brush insulated from and mounted in the walls of the casing 41, bears upon said contact ring. A plurality of brushes are provided, one for each of the magnetic

95

100

105

110

115

120

125

130

clutch elements, and are denoted respectively by the reference numerals 61^a and 61^b, and 62^c and 62^d. Secured upon the rear exterior wall of the casing 41, is an insulating plate 63, on which the respective relays for the different magnetic clutch elements are mounted. The relays are denoted respectively by the reference numerals 64^a, 64^b, and 65^c and 65^d, each of said relays being provided with an armature bar denoted respectively by the reference numerals 66^a, 66^b, and 67^c and 67^d. Also mounted upon said insulating plate 63, are a pair of terminals for each of said respective armature bars, said terminals being denoted respectively by the reference numerals 68^a, 68^b, 69^a, 69^b, 70^c, 70^d, and 71^c and 71^d, and said armature bars are pivoted and normally closed against one of said terminals provided therefor and when the relay is energized, swing in position to close against the other thereof.

Secured upon the side wall of the operator's compartment in the body 3, as shown in Figs. 1 and 2, is an insulating plate 72, which, as shown in the detail view in Fig. 15, has mounted thereon long contacts or terminal members 73^a and 73^b, and 74^a and 74^b, respectively, and connected in the controlling cable 15, is an insulating rod 75, having secured thereon brushes 76^a and 76^b, respectively, constructed as shown in Fig. 16, which bear against said long contact members 73^a and 73^b, and 74^a and 74^b, as well as against long contact terminal members 77^a and 77^b, respectively.

As already stated, the main driving shaft 46, for the clutch elements is connected to the power plant or engine 48, of the aeroplane for movement thereby, but an auxiliary emergency mechanism is provided, as shown in Fig. 17, to drive said main clutch driving shaft 46, in the event that the engine 48, becomes inoperative or is stopped or slowed down an excessive amount for any reason whatsoever. As shown in Figs. 17 and 18, the shaft 46, has secured thereon a ratchet wheel 78, and abutting thereagainst and secured to any shaft 79, driven by the engine, is a plate or disk 80, having a plurality of spring impelled pawls 81, thereon, adapted to engage the ratchet wheel and thus impart a drive to the shaft 46, from the shaft 79. Secured upon the engine driven shaft 79, is a pulley 82, associated with a centrifugal governor 83, which is connected to a conductor plate 84, feathered on said shaft 79, so that when said shaft 79, is rotating the centrifugal governor acts to draw said conductor plate or disk 84, inwardly against a brush contact 85. A generator 86, has a belt 87, trained around the pulley thereof, and said belt is also trained around the pulley 82, to receive a drive from the shaft 79, and the leads 88 and 89, respectively, from said generator, lead to a storage

cell 90, and to the brush 85. Another brush 91, bears upon said conductor disk 84, and a lead therefrom, denoted by the reference numeral 92, is connected to the other terminal of the storage cell 90, so that under a normal operation of the engine 48, the circuit is closed through the generator 86, and storage cell 90, so that the storage cell is charged by the generator and the shaft 46, is of course driven from the engine driven shaft 79. A brush 93, similar to the brush 85, is mounted in a position to contact the disk 84, when the engine driven shaft 79, slows down sufficiently such that the governor 83, thrusts said plate along the shaft, thus establishing a circuit through the lead 92, and a lead 94, connected to said brush 93, said lead 94, being connected to a motor 95, with the other lead 96, from said motor connected to the storage cell 90. Said motor is adapted to drive the shaft 46, by means of a belt 97, trained about a pulley 98, mounted on said shaft 46, and of course when the motor 95, is driving the shaft 46, the pawls 81, merely click over the ratchet wheel 78, so that the engine driven shaft 79, is not rotated by the motor.

An auxiliary stabilizing mechanism is also provided adapted to operate automatically to aid in preserving the equilibrium of an aeroplane by restoring the same to a safe angle of incidence when deviated therefrom under any conditions of flight. This auxiliary mechanism operates automatically to effect a shifting of the longitudinal instrument board 18, which is pivotally mounted for the purpose, as already mentioned. A plane or surface 101, is accordingly mounted as shown in Fig. 2, at one side of the body 3, of the aeroplane upon a transversely extending horizontal shaft 102, journaled in suitable bearings provided to support the same. At its ends said shaft is provided with a switch or contact arm 103, shown in detail in Figs. 19 and 22, having a resilient contact element 104, adapted to sweep over an insulating plate 105, provided with an arc shaped contact 106, and two point contacts or terminals 107 and 108, respectively.

Pivotedly connected to a handle on the upper edge of said pivotally mounted instrument board 18, is a long lever or connecting rod 109, which is in turn connected to a rod 110, which extends into a double solenoid 111, and is provided therein with a magnetic cylinder 112, adapted to be actuated by either one of the magnetic coils of the double solenoid 111. As shown in detail in Fig. 20, coiled springs 113, are disposed at each end of said magnetic cylinder 112, to normally resist movement thereof and hold the same spaced in a neutral position at the middle of said double solenoid. One terminal of each of the coils of the double solenoid is grounded and the other terminals 130

thereof are connected to the terminal contacts 107 and 108, by wires 114 and 115, respectively, and connected to the terminal 106, is a wire 116, leading from a suitable 5 source of current.

Referring now to the wiring diagram shown in Fig. 24, a battery or any suitable source of E. M. F. is denoted by the reference numeral 117, one terminal of which 10 is grounded and the other of which branches and leads to the respective switches 118 and 119. Connected to the switch 119, is a main line wire 120, and connected thereto is the central or main lateral plumb lever 21, of 15 the lateral control instrument board 19, by means of a wire 121. Connected to said wire 121, is a wire 122, which branches into the leads 123^a and 123^b, leading to the armature bars 66^a and 66^b, respectively, of the 20 relays. One terminal of each of the respective relays 64^a and 64^b, is grounded, and the other terminals thereof are connected by wires 39^a and 39^b, respectively, to the respective contact levers 32^a and 32^b. The contacts 68^a and 68^b, respectively, of said 25 relays adapted to be closed by the armatures thereof, are connected by means of wires 124^a and 124^b, respectively, to the terminals 29^a and 29^b, respectively, on the lateral control 30 instrument board 19. The other terminals 69^a and 69^b, respectively, on said relays are connected by means of wires 125^a and 125^b, respectively, with the contact terminal members 74^a and 74^b, respectively. 35 Connected to the wires 39^a and 39^b, respectively, are wires 126^a and 126^b, respectively, which lead to the terminals 28^a and 28^b, respectively, on the instrument board. The respective terminals 23^a and 23^b, on each 40 side of the main lateral plumb lever 21, are connected directly to the respective right and left lateral control plumb levers 26^a and 26^b, by means of wires 127^a and 127^b.

The resilient terminal members 30^a and 45 30^b, respectively on the lateral control instrument board 19, are connected to one another by a wire 128, which leads to the magnetic brake 129, adapted when energized to thrust its armature frictionally against the 50 large gear wheel 57. The other terminal of said magnetic brake 129, is of course grounded. Wires 130^a and 130^b, are connected to the contact terminal members 77^a and 77^b, respectively, and said wires lead to brushes 55 61^a and 61^b, respectively, on the magnetic clutch. A similar scheme of electrical connections to that already described is provided for mechanisms on the board 18, and the magnetic clutches 50^c and 50^d, and respective 60 relays 65^c and 65^d, acting through secondary longitudinal control plumb levers 26^c and 26^d, and a single central main or main longitudinal control plumb lever 131.

The operation is as follows:

65 Referring to Figs. 3 and 24, the position

of the parts illustrates the relation thereof when the gravity acting or plumb levers depend in normal position, that is, the vehicle on which the instrument boards are connected, is on even keel or at least in a normal attitude of flight. The mechanisms are capable of actuating the controlling means of the vehicle when the same is deflected from its proper attitude in a number of different ways, for instance, one board and its 70 associated mechanisms having three possible phases of operation according to different degrees and different intensities of deflection of the vehicle. The operation of the auxiliary surface 101, introduces still 75 another phase of control of the machine, where dangerous conditions of flight obtain without causing a re-adjustment of the mechanisms on the instrument boards, particularly the instrument board for longitudinal control of the machine. The operation of the particular mechanisms for each of the instrument boards is identical, although the mechanisms of the board 18, are connected to operate the longitudinal controls of the machine and the mechanisms of the lateral control board 19, to operate the lateral controls thereof. In the operation described in the following, reference only 80 will be made to the operation of the mechanisms on the lateral control board 19.

First assume a tilting of the aeroplane about its longitudinal axis, resulting in a depression of the right wing and an elevation of the left wing; the lateral control instrument board 19, will be tilted a slight amount in a clockwise direction so that the central gravity acting or lateral control plumb lever 21, will receive moved into contact therewith the terminal 23^a. A circuit will thus be 100 established through the main lateral control plumb lever 21, contact 23^a, wire 127^a, plumb lever 26^a, resilient contact member 27^a terminal 28^a, with which the resilient contact member remains in contact as the board is 105 tilted, wires 126^a and 39^a, to relay 64^a, thence by ground to battery 117, thence through switch 119, and main lead wire 120, and wire 121, to main lateral control plumb lever 21. The current through the relay 64^a, causes the 110 same to be energized, thus moving the armature bar 66^a, into contact with the terminal 69^a, and a secondary circuit is set up from the source of E. M. F. 117, through switch 119, main lead wire 120, wire 121, wire 122, 115 branch wire 123^a, to relay armature bar 66^a, contact 69^a, wire 125^a, contact element 74^a, brush 76^a, contact element 77^a, wire 130^a, to clutch 49^a, and thence by ground returning to battery 117. The energizing of the clutch 120 49^a, of course causes the gear mechanisms to rotate whereby the control lever 6, of the aeroplane is shifted to manipulate the controls thereof. The tilt of the aeroplane will 125 thus be arrested and corrected, and as the 130

aeroplane returns to normal flying attitude the lateral control board 19, of course moves therewith, thus causing the contact terminal 23^a, to retreat from the main lateral control 5 plumb lever 21, breaking the circuit to the relay 64^a, so that the armature thereof is released, thus breaking the secondary circuit to the clutch 49^a, so that actuation thereof cases and the springs 6^a, on the control lever 10 6, of the aeroplane serve to return the controls to normal or neutral position. The momentum of the aeroplane on its return movement continues the movement of the aeroplane back to normal, even though the release 15 of the controls takes place prior to the time at which the aeroplane resumes its normal attitude of flight. Thus over-control or tilting of the aeroplane in an opposite direction due to over-manipulation or over-control of the controlling means, is avoided.

For a second phase of operation typical of the operation of either of the instrument boards, assume that the aeroplane is again tilted, that is, the right wing depressed and 20 the left wing elevated a greater amount than assumed in the preceding instance; then the movement of the lateral control instrument board 19, will again take place, but to a greater degree. This movement of 25 greater magnitude, as pointed out in the foregoing, will cause the same sequence of operation to take place as in the preceding instance described, but inasmuch as the tilting movement of the aeroplane is not arrested but continues on a further amount, a second series of operations will take place. The main lateral control plumb lever 21, will receive the contact 23^a, thereagainst, whereby said plumb lever will be carried 30 with the lateral control board 19, as the board is tilted with the aeroplane, and since the deflection of the aeroplane is of greater magnitude than in the preceding instance described, the contact point 28^a, which is 35 normally in circuit with the right lateral control plumb lever 26^a, will recede therefrom, thus breaking the circuit to the relay 64^a, while, on the other hand, the pivoted arm 32^a, which has frictional engagement 40 with its pivot in the board 19, and tending to move as it does with said board 19, will close contact with the right lateral plumb lever 26^a and as a consequence, a circuit will be immediately established through said relay 64^a, to maintain the relay energized.

The relay 64^a, thus energized, holds the relay armature bar 66^a, in contact with the terminal 69^a, thus establishing a secondary circuit from the source of E. M. F. 117, wire 60 120, wire 122, branch wire 123^a, armature bar 66^a, terminal 69^a, wire 125^a, to contact element 74^a, through brush 76^a, contact element 77^a, thence by ground to source of E. M. F. 117, so that the controls of the aeroplane will be manipulated a further degree

than in the preceding instance described by movement of the cable drum from the gear of the magnetic clutch 49^a. Thus the aeroplane controlling means actuated by the cables 4 and 5, will be kept in movement beyond that point at which the movement of the aeroplane was arrested in the first instance described. This will finally cause the brush 76^a, to move from the contact element 74^a, so that the circuit will be broken and upon again moving into contact therewith an intermittent making and breaking of the circuit will be set up and take place as long as the relay is energized to hold the controls substantially at a fixed adjusted position.

Finally, however, the aeroplane will begin a return tilting movement, moving the lateral control board 19, therewith, and this causes the friction arm 32^a, to swing out of contact with the right lateral plumb lever 26^a, immediately breaking the circuit to the relay, causing the armature bar 66^a, to swing into contact with the terminal 68^a, and de-energizing the clutch 49^a. The movement of the armature bar 66^a, into contact with the terminal 68^a, however, closes the brake circuit from point 29^a, which has moved into contact with resilient member 30^a, wire 124^a, terminal 68^a, armature bar 66^a, wire 123^a, wire 122, wire 121, wire 120, source of E. M. F. 117, thence by ground to brake coil 129, wire 128, to contact member 30^a, thus completing the circuit. The actuation of the brake of course serves to lock the mechanisms in an adjusted position whereby the controls are held rigid against the stress of the springs 6^a, of the controlling lever, while the plane is on its return movement from tilted position to normal attitude of flight.

As the aeroplane returns almost completely to normal, the terminal contact 29^a, will finally recede from the resilient contact 30^a, sufficiently to break the circuit, thus breaking the circuit to the brake 129. The springs 6^a, then operate instantly to restore the controls to normal or neutral position. Closure of the contact 28^a, by resilient element 27^a, of the right lateral control plumb lever 26^a, will next take place just before the machine reaches normal to close the magnetic clutch circuit for the time being, but the momentum of the aeroplane returning under the effect of the brake held controls, will have made the effect of actuation of the controls, due to closure of the contact 28^a, entirely negligible.

The next phase of operation for consideration is a maximum tilting of the aeroplane of a magnitude greater than the first two instances described, and one that cannot be adequately arrested nor rapidly enough by movement of the controls in a manner and to such a limit as described in the first two cases. Assume the first and second phases of operation of the parts of the apparatus

to have taken place, so that the tilting of the aeroplane beyond extreme movement of the instances described continues, and of course movement of the instrument board 19, there-
 5 with. Under such conditions the frictional arm 32^a, is in contact with the right lateral control plumb lever 26^a, and the terminal 23^a, is in contact with the main lateral control plumb lever 21, and the brush 76^a, is at
 10 an extreme end of the contact element 74^a. In view of the magnitude of deflection of the aeroplane from normal attitude, however, the adjustment of the controls effected by such a position of the parts of the control
 15 boards has been insufficient to return the aeroplane to normal position or arrest the movement of the plane, and as the tilting angle becomes greater and the board moves therewith the frictional arm 36^a, will be
 20 moved downwardly with the board 19, to contact the right lateral control plumb lever 26^a. A circuit will now be established from the source of E. M. F. 117, main lead wire 120, wire 121, plumb lever 21, contact 23^a,
 25 wire 127^a, right lateral control plumb lever 26^a, frictional arm 36^a, wire 38^a, contact element 73^a, brush 76^a, contact element 77^a, wire 130^a, magnetic clutch 49^a, thus actuating the controls and causing movement of the brush
 30 76^a, out of contact with the contact element 74^a, which, however, will have no effect upon the circuit, the current leaving the clutch 49^a, and returning by ground to source of E. M. F. 117.
 35 The magnetic clutch 49^a, is therefore operated independently of the relay 64^a, and will continue to operate until the amplitude of movement or adjustment of the controls is such that the brush 76^a, slides off and out
 40 of contact with the element 73^a, this being the point of limiting adjustment of the aeroplane controls. At this point the springs 6^a, on the control levers of the aeroplane will tend to restore the aeroplane controls
 45 to normal or neutral, thus moving the brush 76^a, back into contact with the contact element 73^a, thus energizing the clutch 49^a, to again operate the controls and shift said brush out of contact, and this making and
 50 breaking of the circuit at the limiting position of the controls continues until the aeroplane begins its return tilting movement to normal attitude.
 Of course, during a return movement of
 55 the board 19, the various mechanisms thereon are operated to close the electrical circuits in the sequence described with reference to the operation in the first two instances described, so that manipulation of the controls
 60 will take place until the aeroplane has almost returned to its normal attitude, and the controls will then be released to permit the aeroplane to continue its return under its own momentum to its original or normal attitude. It is obvious that the lateral con-
 trol board 19, and its mechanisms will operate to restore the machine to normal attitude, even though a deflecting effect occurs during a return movement of the aeroplane to normal from a deflected position. The de-
 70 vice is immediately sensible to deflecting movements of the aeroplane, and as pointed out operates in three different ways, accord-
 75 ing to three different degrees of deflection of the aeroplane, thus acting to adjust the controls to restore the aeroplane to normal attitude before the deflective movements may have become so serious as to cause accident.
 In a deflecting movement which takes place opposite to that described, that is, re-
 80 sulting in a deflection of the left wing and an elevation of the right wing, exactly the same series of operations take place as de-
 scribed, except that the gravity acting left lateral control plumb lever 26^b, switch con-
 85 tact element 73^b, 74^b, 77^b, and brush 76^b, and magnetic clutch 49^b, as well as the other b connections, enter into the operation.
 Although the lateral control board 19, may be adjustably mounted in the body of the machine, it, however, should never be necessary to adjust the angle of said board with respect to the aeroplane, for the reason that the board and its mechanisms will act automatically to insure proper banking of the machine in making a turn, due to centrifugal force acting upon the lateral control plumb levers. That is to say, when the proper tilt of the aeroplane has been acquired, due to a lateral swing of the lateral control plumb levers when a turn is made, the centrifugal force will maintain said lateral control plumb levers in the same relative position with respect to the lateral control instrument board 19, as the levers would
 100 have when the aeroplane is flying horizontally and the board is in normal horizontal position. Any deviation from the banking angle will cause closure of the circuit to set the controlling means of the aeroplane in
 105 operation in the same manner as a deflection of the aeroplane from normal flying attitude to cause return of the aeroplane to the proper banking angle. When the aeroplane is straightened out upon its course, the centrifugal force made evident upon the lateral control plumb levers vanishes, and said plumb levers swing downwardly by gravity
 110 to close certain of the circuits to thereby operate the controls of the aeroplane to re-
 115 turn the aeroplane from its banking position back to normal attitude for straight-
 away flight.
 The operations of the lateral control in-
 120 strument board 18, and its associated mech-
 anisms are identical with those of the lateral control board 19, described, the same oper-
 125 ating to properly take care of longitudinal deflections of the aeroplane from a true or normal attitude of flight which would tend
 130

to move the machine to a dangerous position or attitude. However, a flying machine may encounter air conditions unknown to the operator which would not affect the angle of 5 the machine with respect to earth, yet its attitude or relation to the air may be such that a dangerous angle of incidence is brought about, so that the stability of the machine in the air is a matter of serious moment. Fig. 10 2 illustrates the connection of the auxiliary stabilizing plane upon the machine, and Figs. 19 to 23 inclusive, together with a portion of the wiring diagram 24, illustrate the operating mechanisms thereof; Fig. 19 showing 15 diagrammatically the manner in which the longitudinal control instrument board 18, is adapted to be shifted due to movement of the auxiliary surface 101. If the aeroplane should be tilted longitudinally for any 20 cause whatsoever, as for instance, by flying into a very gradual ascending or descending current of air, so that the air flow on the opposite surfaces of the plane 101 would be equal the same as for normal attitude of 25 flight, the plane 101, would not be tilted with reference to the aeroplane and yet the aeroplane would be shifted as a whole out of its path of flight, so that its angular position with respect to the earth would be changed. 30 When such a tilting of the aeroplane occurs the longitudinal control instrument board 18, must of course necessarily move with the body of the aeroplane into its angled position, thereby causing a new adjustment of 35 the longitudinal control plumb levers with reference to the contact members associated therewith to take place, thus closing certain electrical circuits in the manner described with reference to the lateral control instrument board 19, to cause actuation of the 40 aeroplane controls to return the aeroplane to its normal attitude of flight.

However, in the event that the machine when flying in a predetermined course, either 45 ascending, descending, or traveling horizontally, is met by a current or gust of air, either flowing upwardly or downwardly, or the machine suddenly passes into a moving stratum of air which has an upward or 50 downward movement with respect to the direction of flight of the machine, the plane surface 101, will sense the abnormal conditions of flow of air which of course sets up a new attitude of flight of the machine with 55 respect to the air, although the angle of the machine with respect to the earth may not have changed, and this new attitude of the machine with respect to the relative air, may create a very dangerous situation. The effect 60 of the new atmospheric conditions encountered upon the surface 101, will be to swing the surface and thereby move the switch bar 103, to close against one or the other of the contacts 107 or 108, as the case 65 may be. This energizes one of the coils of

the double solenoid 111, to cause movement of the armature 112, either in one direction or the other therein, to, through the long link 109, tilt the pivotally mounted longitudinal control instrument board 18. As a 70 consequence, electrical circuits are closed to actuate the magnetic clutches and effect an adjustment of the longitudinal controls of the aeroplane to re-adjust the same to a new and safe attitude of flight. 75

It is apparent, therefore, that practically any conditions which tend to affect the stability of a machine in flight are immediately and automatically taken care of to preserve the equilibrium of the machine and insure 80 absolute safety of operation thereof.

I am aware that various details of construction may be varied through a wide range without departing from the principles of this invention, and I therefore do not pur- 85 pose limiting the patent granted otherwise than necessitated by the prior art. 90

I claim as my invention:

1. A stabilizing device for aeroplanes comprising a plurality of plumb levers disposed laterally of the aeroplane to permit relative movement of the aeroplane and plumb levers, and a plurality of plumb levers disposed longitudinally of the aeroplane to permit relative movement between the aeroplane and plumb levers, each of said plumb levers independently mounted for movement, electrical circuits associated with said plumb levers, a plurality of magnetic clutches adapted to be selectively set in operation when said electrical circuits are operated by the co-action of certain of said plumb levers and mechanisms adapted to be actuated by said magnetic clutches to operate the controls of the aeroplane. 95 100 105

2. A stabilizing device of the class described comprising a plurality of instrument boards, plumb levers mounted independently of one another on each thereof, electrical circuit contact members associated 110 with said instrument boards and with said plumb levers, and a plurality of magnetic clutches set in operation by closure of said electrical contacts by movement of said boards with respect to said plumb levers to 115 operate the controls of the aeroplane.

3. In a stabilizer of the class described, transversely disposed and longitudinally disposed instrument boards, a plurality of electrically connected plumb levers mounted independently of one another on each of said boards, contact members associated with said plumb levers and boards, and magnetic clutches adapted to be selectively set in operation by closure of a contact between said 120 plumb levers and boards to operate the controls of the aeroplane. 125

4. In an automatic controlling device for vehicles a pair of instrument boards mounted at right angles to one another, a 130

plurality of independently mounted plumb levers on each thereof, electrical contacts associated with said boards and plumb levers adapted to be closed by relative movement 5 therebetween, and magnetic clutches set in operation when certain of said contacts are closed thereby to operate the controls for the vehicle.

5. In an automatic controlling device for 10 a vehicle a pair of instrument boards, one rigidly mounted and the other pivotally mounted on the vehicle, a plurality of plumb levers mounted on each of said boards, electrical contacts associated with said plumb 15 levers and boards, and mechanisms adapted to be set in operation by closure of said contacts to operate the controls of the vehicle.

6. In a stabilizer of the class described 20 for an aeroplane a pair of instrument boards mounted at right angles to one another, one of said boards rigidly mounted and the other pivotally mounted on said aeroplane, a plane surface connected when affected by air gusts 25 to tilt the latter of said instrument boards, a plurality of plumb levers on each of said instrument boards, contacts associated with said plumb levers and boards, and mechanism set in operation by closure of said contacts to operate the controls of the aeroplane.

7. In a stabilizer of the class described, a plurality of instrument boards, a plurality of plumb levers on each thereof, electrical 35 contacts associated with each of said boards and plumb levers, a plurality of magnetic clutches electrically connected to the contacts, and mechanisms operated by said clutches when said contacts are closed to 40 actuate the controls of a vehicle.

8. In a stabilizing device of the class described, a plurality of instrument boards, one rigidly secured to and the other pivotally mounted upon an aeroplane, mechanisms 45 on said boards adapted to effect closure of electrical contacts when said boards are moved from normal, automatic means sensible to upwardly flowing and downwardly flowing air currents adapted to tilt 50 said pivotally mounted board, and means set in operation by the mechanisms on said boards to actuate the controls of a vehicle.

9. In a stabilizing device for vehicles, a plurality of normally unconnected electrical 55 contacts, means operating to connect the same when the vehicle is diverted from its course, a plurality of magnetic clutches, means normally driving the same from the power plant of the vehicle, a generator, motor and storage battery associated therewith whereby said generator is driven by the power plant to charge said storage battery, a governor cut out mechanism to connect said motor to said storage battery in the 60 event of stoppage of said power plant to

drive said magnetic clutches by said motor, said magnetic clutches electrically connected to said contacts to actuate driving mechanisms when said contacts are closed, and connections between said mechanisms and the 70 controlling devices of the vehicle for actuation thereby.

10. In a device of the class described, the combination with the power plant of a vehicle, of means driven thereby, automatically acting mechanisms adapted to energize 75 said means, controlling devices adapted to be actuated by said means when the same are energized, and auxiliary mechanisms adapted to drive said means independently 80 of the power plant when the speed of operation of said power plant falls below a certain predetermined point.

11. In a device of the class described, an instrument board, a plurality of plumb 85 levers thereon, each independently mounted, contacts associated with said plumb levers and said boards, one of said plumb levers adapted with another of said plumb levers to close electrical circuits when said board 90 tilts in one direction, and the other of said plumb levers together with said second mentioned plumb lever adapted to close other circuits when the board is tilted in the opposite direction, and means set in operation 95 by the closure of the circuits to operate the controls of a vehicle.

12. In a stabilizing device for vehicles of class described, a plurality of boards, a plurality of plumb levers mounted independently of one another on each thereof, contacts associated with said plumb levers and boards, one of said plumb levers together with another thereof on one of said boards adapted to close certain of said contacts to 100 effect a circuit between the plumb levers closing the contacts when said board is tilted in one direction, and a third plumb lever on said board operating with said second mentioned plumb lever to close other contacts to 105 effect a circuit between the second and third plumb levers when the board is tilted in the other direction, and means set in operation by the closure of said contacts to operate the controls of a vehicle.

13. The combination with a flying machine and its controls, of a power mechanism for actuating said controls, comprising constantly driven magnetic clutches, a gear train adapted to be driven thereby, drums 120 associated with said gear trains, cables connected to said controls and wound about said drums, a plurality of instrument boards mounted on the flying machine, and a plurality of independently mounted gravity 125 levers on each thereof electrically connected to one another and to said power mechanism to cause energization of said clutches to actuate certain of the controls when movements of the flying machine cause relative 130

movements between said levers and said instrument boards.

14. The combination with a vehicle and its controls, of magnetic clutches connected to actuate the vehicle controls, a plurality of instrument boards each having a plurality of gravity acting levers pivotally mounted thereon, said levers mounted independently of one another, and electrical circuits between said levers and said magnetic clutches to cause actuation of the controls due to relative movement between said respective levers and said instrument boards.

15. The combination with a vehicle and its controls, of a power means for actuating the vehicle controls, and mechanism connected to control the operation of said power means comprising a stationary and an adjustable board, a plurality of gravity acting levers pivotally mounted on each thereof, and electrical circuits between said levers and said power means.

16. The combination with a vehicle and its controls, of magnetic clutches connected to actuate certain controls, and a plurality of independently operable mechanisms for effecting a selective operation of said magnetic clutches for actuation of said controls, and a plurality of gravity acting levers forming a part of each of said mechanisms.

17. The combination with a vehicle and its controls, of magnetic clutches adapted to be selectively operative, and a plurality of sets of gravity acting plumb levers controlling the actuation of said magnetic clutches, each of said plumb levers of each set movable independently of the other, electric circuits between each of said plumb levers and said magnetic clutches, certain circuits adapted to be closed by one set of said plumb levers for one phase of operation of said controls and other circuits adapted to be closed by certain other of said plumb levers for another phase of operation of said controls, and mechanisms operated by said magnetic clutches when the circuits are closed to actuate the controls of a vehicle.

18. The combination with a vehicle and its controls, of magnetic clutches selectively operable to selectively actuate said controls, a plurality of instrument boards each provided with mechanisms automatically operable and connected to cause a selective operation of said magnetic clutches, one of said instrument boards movably mounted to permit automatic adjustments thereof under certain conditions.

19. The combination with a vehicle and its controls, of a selectively operative means connected to selectively operate said controls, a pair of instrument boards provided with mechanisms connected to selectively operate said means, one of said boards rigidly mounted and the other movably mounted to permit automatic adjustment thereof,

and a plurality of gravity acting means forming a part of the mechanisms on each of said boards.

20. The combination with a vehicle and its controls, of means for actuating the vehicle controls, and a plurality of sets of independently operable automatic mechanisms connected to cause operation of said means, each comprising a main gravity acting plumb lever, secondary gravity acting plumb levers, situated between each of said secondary plumb levers and the main plumb lever adapted to be closed by the adjustments of the main and secondary plumb levers, said mechanisms adapted to cause operation of said means different degrees and for different periods of time for actuation of said controls, in accordance with the degree of adjustment imposed upon said mechanisms by movement of the vehicle.

21. The combination with a vehicle and its controls, of means connected to actuate the vehicle controls, and automatically acting mechanisms each independently operable to effect a selective operation of said means for a selective actuation of said controls comprising instrument boards, a plurality of gravity acting means on each thereof, electric circuits between said gravity acting means, said boards, and said means, and a plurality of contact members forming a part of said circuits on each of said boards adapted to be brought into operation selectively according to the degree of relative adjustment between said gravity acting means and said boards.

22. The combination with a vehicle and its controls, and power mechanism for operating said vehicle of mechanism for adjusting the vehicle controls and normally connected to be driven by said power mechanism, said control mechanism comprising a plurality of groups of independently operating circuit closure elements adapted to co-act with one another to cause manipulation of the controls of the vehicle and an auxiliary driving means for said controlling mechanism adapted to operate the same automatically upon failure of the vehicle power mechanism to operate the same.

23. The combination with a vehicle and its controls and power mechanism for operating the controls of the vehicle, and for driving said vehicle, automatic means controlling the application of power to said vehicle controls and auxiliary means operable independently of said power mechanism to operate said vehicle controls in the event of failure of said power driving mechanism.

24. The combination with a vehicle and its controls of power mechanism for driving said vehicle, connections between the controls of the vehicle and the power mechanism, means controlling the application of power through said connections to said ve-

hicle controls, to automatically preserve the stability of said vehicle and means for operating the vehicle controls independently of said power mechanism and operating automatically to transmit power through said connections in the event of failure of said power mechanism.

25. The combination with a vehicle and its controls of power mechanism for driving the vehicle, connections between the same and the vehicle controls, automatic means controlling the application of power to said

controls from said power mechanism, and automatic means adapted to transmit power to said vehicle controls for operation thereof in the event of failure of vehicle power mechanism. 15

In testimony whereof I have hereunto subscribed my name in the presence of two subscribing witnesses.
